UNITED STATES PATENT OFFICE.

GEORGE ALBERT LYON, OF PHILADELPHIA, PENNSYLVANIA.

AUTOMOBILE BUFFER DEVICE.

Application filed June 14, 1921, Serial No. 477,586. Renewed September 1, 1922. Serial No. 585,831.

To all whom it may concern:

Be it known that I, GEORGE ALBERT LYON, a citizen of the United States, and resident of Philadelphia, county of Philadelphia, State of Pennsylvania, have made a certain new and useful Invention Relating to Automobile Buffer Devices, of which the following is a specification, taken in connection with the accompanying drawing, which 10 forms part of the same.

This invention which is a continuation in part of that disclosed in my copending application Serial No. 424,685 filed November 17, 1920, relates especially to resilient buffer 15 or bumper devices for automobiles or other vehicles in which the spring steel or other resilient strips or members have clamped thereto, a resilient sheet metal or other contact clamping or connecting device having a 20 vertically wide contact face throughout the central part of the buffer, and preferably having integral clamping members to adjustably or otherwise clamp thereto the one or more buffer front strips. Such vertically 25 extending clamping devices may be advantageously formed of spring steel strip or sheet metal three sixteenths to three eighths of an inch thick more or less, and having if desired vertically separated contact portions, one of which may in some cases be substantially in line with the buffer front strips one or more of which may extend across the 30 buffer front behind or adjacent the cooperating contact clamping member. These different front contact portions may be separated from each other vertically to the desired extent, so as to secure a front collision face which may be substantially flat if desired, and which may have a vertical 35 width of six or eight inches more or less in some cases. With the present type automobiles in which the front frame members are arranged quite close to the ground, it is often desirable to have this collision contact face extend upward more than downward with respect to the buffer front strip or member, and any of these types of clamping 40 contact devices may if desired have each end formed with one or more integrally stamped or otherwise formed clamping members thereon, some of which may more or less fit around or enclose the inwardly extending 45 ends or other parts of the cooperating buffer front strip so as to have considerable aligning action with respect thereto. In many 50 cases it is desirable to form this spring steel

or other contact clamping member with a polished nickel plate finish, so as to have a desirable appearance when secured upon the black finished or other spring steel strip 55 buffer members with which it may be used.

In the accompanying drawing showing in a somewhat diagrammatic way various illustrative embodiments of the invention,

Fig. 1 is a perspective view of one form 60 of buffer.

Figs. 2 to 4 are transverse vertical sections taken substantially along the corresponding section lines of Fig. 1.

Fig. 5 is a perspective view of another 70 construction.

Fig. 6 is a plan view thereof; and

Figs. 7 to 11 are perspective views of other 75 illustrative constructions.

The automobile buffer may have any desired or suitable construction and preferably comprises one or more pieces of spring steel strip which at the buffer front, may in some cases be advantageously arranged in overlapping or reinforcing position, or may 80 if desired have these front strips extend toward and in line with each other without substantial overlapping. As is indicated in Fig. 1, a modified Lyon type spring buffer is shown comprising the attaching arm or 85 member such as 1 connected with the end loop 4 through the outwardly extending bend or curved portion 3. This spring steel strip may be extended inward from the end loop 4, so that this front strip 9 may extend to about the point 8 and have this end slotted if desired like the corresponding front strip 7 of the other spring steel strip buffer member, which may have an end loop 6 curved portion 5 and attaching member 2. 90

Instead of or in addition to the usual clamping or connecting devices these buffer front strips or impact receiving members 7, 9, may be adjustably or otherwise connected by contact and clamping devices in the form 100 of an integral sheet metal or spring steel member which may have a wide vertical contact face adjacent the center of the buffer. As is shown in Fig. 1 this contact clamping device may have several vertically 105 separated contact portions such as 11, 12 which may be stiffened and strengthened by forming reinforcing ribs such as 13, 19 on some or all of the substantially horizontal edges of this member. At least the upper 110 edges are preferably formed with such integral stiffening ribs which besides strength-

ening the member, gives it a more pleasing appearance. In some cases the central slot or opening 17 may have a considerable horizontal extent and if desired the ends of this opening or slot may be gradually reduced so as to extend nearly in line with the attaching members in some cases. Any suitable form of connecting or clamping means may be used to adjustably or otherwise connect the ends of this contact clamping device to the buffer front strips 7, 9 which may in some cases have slotted ends 8, 10 formed with the slots or apertures 39 for clamping connecting purposes. In some cases one or more round end clamping bolts such as 30 may extend through each of the clamping ends of the contact device and through such slots or apertures in the buffer front strip, so as to make strong or rigid contact therewith. It is however, desirable to form each of these clamping ends of the contact device with one or more integral enclosing clamping members such as 18, which as indicated in Fig. 4 may be formed by bending around integral tongues or projections on this spring steel plate so that a clamping bolt 20 may tighten these strips securely around the buffer front member within. The adjacent reinforcing ribs may as indicated extend out adjacent these front strips so as to have an important vertical aligning action in connection therewith, and promote the strength and rigidity of this clamping connection of the buffer elements.

35 In the embodiment shown in Figs. 5 and 6, the contact and clamping device may have if desired a substantially flat or straight central contact face comprising the more or less separated contact members 21, 22 of generally arched or curved form, so as to have a somewhat lenticular opening 23 between them. The edges of these vertically separated contact portions may advantageously be formed with rearwardly projecting stiffening ribs such as 13, which of course, considerably add to the strength and stiffness of this central contact member under collision conditions especially if it is made of tempered spring steel. In some cases it is desirable to have the contact member formed with end connector portions such as 24, 25 which extend out a considerable distance toward or to the end loops 4, 6 of the front strips and these connector portions may as indicated in Fig. 6 be rearwardly bent or inclined and be preferably formed substantially straight where they are to be adjustably connected with the cooperating front strips. Suitable ribs may be formed on the edges of these connector portions strengthening the construction at this point, and also promoting the vertical alignment of the cooperating connected parts which may be clamped or connected together in any desired way. Integral enclosing clamp-

ing members may be used for this purpose and several such integral clamping members 18 are shown on each connector end of this wide front contact and clamping device, so as to be tightened around the adjustable front strips 7, 9 when the clamping bolts 26 are tightened. In some cases it is preferable to raise this wide central contact portion of the buffer front somewhat above the center line of its end connector portions and by raising this central part three fourths of an inch or an inch more or less in any of these front designs, the stock for the integral clamping strips or projections can be cut or formed from a strip of sheet metal with a minimum of waste where this particular form of enclosing clamp shown in Fig. 4 is used.

Fig. 7 shows another construction in which the wide contact face of the contact and clamping device is given a somewhat different form, so as to comprise the vertically separated contact portions 27, 29 separated by the taper end slot or aperture 28. If desired this contact portion may be somewhat raised beyond the end connector portions 33 for similar reasons especially since this gives the added height of the front contact face, which is usually desirable with the present low hung automobile frame ends. Similar stiffening and strengthening ribs such as 13 may be formed on this front contact portion and the connector ends may be formed with the aligning or stiffening flanges 32 shown in Fig. 8, so as to facilitate the alignment of the buffer front strips which may be bolted to these ends of the contact device as by one or more bolts 30 and nuts 31.

In the form shown in Fig. 9 the contact and clamping device has two vertically separated strips or contact portions 34, 36, whose outline is determined by the intermediate aperture or slot 35. In this case one of these contact strips or portions may be substantially in line with the connector end portions 33 of this contact device, which may be similarly ribbed and reinforced and bolted or otherwise connected to the buffer front strips 7, 9 in an adjustable or rigid manner.

Fig. 10 shows still another illustrative construction in which the contact clamping device may have a somewhat greater vertical width and strength in its central portion, since only two lenticular apertures or slots 39 are stamped or formed in this contact face. This stamped out material may be more or less formed into the integral stiffening ribs 13 extending around from one or all of the edges of the plate which may have connector end portions 33 bolted or clamped in any suitable way to the buffer front strips. Fig. 11 shows still another construction in which the contact

clamping device 40 has a single wide contact face which may be unperforated if desired and formed with heavy stiffening ribs or flanges 13 at its top and bottom edges.

6 Any suitable lateral extensions or end connector portions 33 may be formed on this contact plate and perforated if desired for one or more connector bolts 30 at each end of the contact plate which may thus be 10 bolted or secured to the one or more buffer front strips such as 7, 9. Where lateral adjustment of these parts is desired, the front strips may be conveniently formed with adjusting slots 39 through which these clamping bolts may pass so as to secure several inches or so adjustment at each end of the buffer.

This invention has been described in connection with a number of embodiments, 20 forms, proportions, parts, arrangements, materials, methods of connection and use, to the details of which disclosure the invention is not of course to be limited, since what is claimed as new and what is desired 25 to be secured by Letters Patent is set forth in the appended claims:

1. The automobile buffer formed of spring steel strip and comprising attaching arms, end loops and connected front 30 strips having inwardly extending substantially straight connector portions, and a resilient sheet metal contact and clamping device formed with ribbed vertically separated central contact portions and with 35 channeled end connector portions extending adjacent said end loops and enclosing clamping members to adjustably and securely clamp each of said front strips at separated points and securely connect the 40 buffer elements.

2. The automobile buffer formed of spring steel strip and comprising end loops and connected front strips having inwardly extending connector portions, and a resilient sheet metal contact and clamping device formed with vertically separately central contact portions and with channeled end connector portions extending adjacent 45 said end loops and integral clamping members to adjustably and securely clamp each of said front strips at separated points and securely connect the buffer elements.

3. The automobile buffer formed of spring steel strip and comprising end loops and connected front strips having inwardly extending connector portions, and an integral contact and clamping device formed with vertically separated central contact portions and with end connector portions 50 extending adjacent said end loops and located somewhat below the center of said central contact portions and integral clamping members to securely clamp each of said front strips and securely connect the buffer 55 elements.

4. The automobile buffer formed of spring steel strip and comprising attaching arms, end loops and connected front strips extending inward toward each other and a resilient sheet metal contact and clamping device formed with ribbed vertically separated central contact portions and with integral enclosing clamping members for said front strips to adjustably and securely clamp each of said front strips at separated points and securely connect the buffer elements.

5. The automobile buffer formed of spring steel strip and comprising attaching arms, end loops and connected front strips extending inward toward each other and a resilient sheet metal contact and clamping device formed with vertically separated central contact portions and with clamping members for said front strips to adjustably and securely clamp each of said front strips at separated points and securely connect the buffer elements.

6. The resilient strip automobile buffer comprising attaching arms, end loops and connected inwardly extending front strips, and a resilient sheet metal contact and clamping device formed with vertically separated contact portions extending substantially between said attaching arms and with integral enclosing clamping members for said front strips to adjustably and securely clamp said front strips at separated points adjacent said end loops and securely connect the buffer elements.

7. The resilient strip automobile buffer comprising attaching arms, end loops and connected inwardly extending front strips, and a contact and clamping device extending across the center of the buffer front and formed with vertically separated contact portions and with integral enclosing clamping members for said front strips to adjustably and securely clamp said front strips at separated points adjacent said end loops and securely connect the buffer elements.

8. The spring strip automobile buffer comprising looped end front strips and a connected vertically extending sheet metal contact and clamping device extending across the center of the buffer front and formed adjacent its ends with a plurality of integral clamping members to secure the same substantially rigidly to the inner ends of said front strips.

9. The spring strip automobile buffer comprising front strips and a connected vertically extending integral sheet metal contact and clamping device extending across the center of the buffer front and formed adjacent its ends with a plurality of clamping members to secure the same substantially rigidly to the inner end of said front strips.

10. The automobile buffer comprising a

- spring strip buffer front and a connected vertically extending integral resilient contact and clamping device extending across the center of the buffer front and having vertically separated central portions and formed adjacent its ends with a plurality of clamping members to secure the same substantially rigidly to the inner ends of said buffer front.
10. 11. The automobile buffer comprising a buffer front and a connected vertically extending integral resilient contact and clamping device extending across the center of the buffer front and having vertically separated central portions and a plurality of clamping members to secure the same to the inner ends of said buffer front.
12. The resilient sheet metal vertically extending contact and clamping device 20 adapted for use with spring strip automobile buffers and comprising rearwardly bent connector ends and a relatively flat front central collision face having vertically separated ribbed reinforced portions 25 and having adjacent each end integral enclosing clamping members adapted to engage and securely hold buffer strips.
13. The resilient vertically extending contact and clamping device adapted for use with spring strip automobile buffers and comprising connector ends and a central collision face having vertically separated ribbed reinforced portions located above the center line of said connector ends and having adjacent each end clamping members 35 adapted to engage and securely hold buffer strips.
14. The one piece spring steel vertically extending contact and clamping device 40 adapted for use with spring strip automobile buffers and comprising separated rearwardly bent clamping ends and a central collision face having vertically separated reinforced portions and having adjacent each end integral clamping members adapted 45 to align and securely hold buffer strips.
15. The spring steel vertically extending contact and clamping device adapted for use with spring strip automobile buffers and comprising separated ends and a central collision face having vertically separated portions and having adjacent each end clamping members adapted to be secured to buffer strips.

GEORGE ALBERT LYON.
